UNITED STATES PATENT OFFICE.

GEORGE B. GALLUP, OF BOSTON, MASSACHUSETTS.

FIRE-EXTINGUISHER.

1,137,202.

Specification of Letters Patent. Patented Apr. 27, 1915.

Application filed August 6, 1914. Serial No. 855,501.

To all whom it may concern:

Be it known that I, GEORGE B. GALLUP, a citizen of the United States, residing at Boston, in the county of Suffolk and State 5 of Massachusetts, have invented new and useful Improvements in Fire-Extinguishers, of which the following is a specification.

This invention relates to a device for extinguishing fires.

10 The object of the invention is to provide a device of the character set forth which will be cheap in construction so that a number of them may be utilized and placed in different rooms or halls of a building without excessive expense.

15 Further the object of the invention is to provide a fire extinguisher which can be readily used by women or children to beat out a fire when it is in its early stages.

20 The object of the invention is also to provide a device of the character set forth which is so simple and its manner of use so self-evident that in the hurry and excitement incident to a fire the same can be 25 used without the exercise of much discretion or judgment.

25 In carrying my invention into practical operation I utilize a casing which is preferably hermetically sealed and contains a 30 liquid consisting of a combination of chemical elements diluted in water which, when brought in contact with fire, tend to produce carbonic acid gas. In the casing is a broom with the handle thereof projecting through the 35 top of the cover of the casing, the cover being made so that it can be easily removed or broken when the broom is withdrawn from the casing. The casing is placed in a convenient position, preferably fastened to 40 a wall, near the floor and the broom can readily be withdrawn to whip out the fire in the early stages of said fire. In whipping out the fire the same will be extinguished by reason of said whipping or 45 flagellation and also on account of the formation of carbonic acid gas due to the contact of the fire with the chemical mixture contained in the broom when the same is withdrawn from the casing.

50 The invention consists in the combination and arrangement of parts set forth in the following specification and particularly pointed out in the claims thereof.

55 Referring to the drawings: Figure 1 is a plan view of my improved fire extinguisher, the handle of the broom being

shown in section. Fig. 2 is a sectional elevation taken on line 2—2 of Fig. 1, a broom being shown in elevation in connection therewith.

60 Like numerals refer to like parts throughout the several views of the drawings.

In the drawings, 5 is a casing provided with ears 6 whereby the same may be screwed to a wall.

65 7 is a flagellator, preferably consisting of a broom which, on account of its cheapness and lightness, forms a convenient utensil for the purpose of this invention. The broom is provided with a handle 8 which 70 projects through a hole 9 in the top 10 of the casing. The top 10 may be made of glass or other brittle substance or it may be made of wood or metal and divided into two parts 11 and 12, the hole 9 being located between the adjacent ends of said 75 parts 11 and 12. Said top is preferably fastened to the casing 5 by a layer of suitable adhesive material 13. The hole 9 and the dividing space 14 between the parts 11 and 12 of the cover 10 are sealed up by a strip 80 of sheet material 15 which is fastened to the top 10 by suitable adhesive material. If the cover 10 is made of glass it is unnecessary to divide the same into two parts, 85 but said glass may be all in one part with the hole 9 extending therethrough and when the broom or flagellator is withdrawn from the casing 5 the glass will be shattered, leaving the broom free for manipulation by the 90 user.

95 The manner in which the device is used and operates is as follows: The device, as hereinbefore set forth, is fastened to a wall by means of screws extending through the ears 6 and into the wall and the casing is filled with a suitable liquid 16 consisting, preferably, of a combination of chemical elements dissolved in water, which, when brought in contact with the fire by means 100 of the broom or flagellator 7 contained within the casing and immersed in the liquid 16, tend to produce carbonic acid gas, the handle 8 of said broom or flagellator projecting through the hole 9 ready 105 to be grasped by the user. In case of fire the user grasps the handle 8, pulls upwardly on the same and either breaks the cover 10 or detaches the same from the casing 5 and the two sides 11 and 12 separate one from 110 the other as well as from the casing 5. The flagellator is then used by the person hold-

ing the same to beat or whip the fire to put out the flames. The action of the broom or flagellator in thus whipping or beating the fire to extinguish the same is two-fold—
5 the jarring of the flagellator tends to extinguish the flames and the chemical liquid contained within said flagellator and upon its surface is sprinkled over the flames and by contact therewith carbonic acid gas is
10 produced which smothers the flames and extinguishes the fire.

While a broom is the preferred means used by me for the flagellator, it is evident that without departing from the spirit of
15 my invention any form of flagellator may be used, so long as the same is adapted to absorb, contain or hold a certain amount of liquid.

Copies of this patent may be obtained for five cents each, by addressing the "Commissioner of Patents,
Washington, D. C."

Having thus described my invention, what I claim and desire by Letters Patent to se- 20
cure is:

A fire extinguisher having, in combination, a receptacle adapted to contain liquid, a top for said receptacle made in two parts, a broom located within said receptacle and 25 a handle for said broom projecting through a hole provided in said top between the adjacent ends of said top.

In testimony whereof I have hereunto set my hand in presence of two subscrib- 30
ing witnesses.

GEORGE B. GALLUP.
